MAGAZINE FASTENING DEVICE FOR
SHOTGUNSLester F. Mulno, Worcester, Mass., assignor to
Harrington & Richardson Arms Co., Worcester,
Mass., a corporation of Massachusetts

Application December 27, 1949, Serial No. 135,078

5 Claims. (Cl. 42—49)

1

This invention relates to magazines for shotguns and particularly to fastening devices therefor.

The principal object of the invention resides in the provision of a tubular magazine for repeating shotguns, said magazine being in the form of a tube and located wholly within the fore end so that it is not visible and does not extend outwardly thereof in any direction.

Another object of the invention resides in the provision of a tubular magazine having a detachable engagement with a stud on the receiver at the rearward end of the magazine, the same underlying the barrel and having a detachable engagement with another stud secured to the barrel and comprising a plunger spring pressed forwardly toward the barrel stud by the magazine spring, said plunger extending through a detachable washer so that when the plunger is retracted against the action of the magazine spring, the washer may be dropped out whereupon the magazine is easily detachable.

Other objects and advantages of the invention will appear hereinafter.

Reference is to be had to the accompanying drawings in which

Fig. 1 is a view in elevation of a shotgun according to the invention with parts in section; and

Fig. 2 is an enlarged view of the detachable connection between the magazine and the barrel stud.

In the present illustration, the firearm is shown as having a barrel 10, a receiver 12, and a stock 14, said stock having a fore end 16 provided with a screw type fastener 18 taking into a stud 20 secured to the receiver 12 at the forward end thereof as at 22. This fastener secures the entire stock to the receiver.

The stud 20 is provided with a shouldered through opening indicated at 24, this opening extending from front to rear and being slightly wider at the forward side thereof than at the rear as clearly shown in Fig. 1.

The barrel is provided with a stud 26 having a relatively small front to rear opening therein for the sliding reception of a plunger 28, said plunger having a head thereon 30.

The magazine itself is made in the form of a tube indicated at 32 and this tube sets against the shoulder in the aperture 24, the smaller part of said aperture accommodating the cartridge follower 34 pressed in a rearward direction by the magazine spring 36, said spring also pressing the plunger 28 into detachable engagement with the barrel stud 26 as shown.

2

The length of the tubular magazine 32 may be approximately the same as the distance between the studs and an apertured washer 38 also receiving plunger 28 takes up the space occasioned by the reception of the rearward end of the magazine in the aperture 24.

With the parts as shown in Fig. 1, the cartridge follower 34 will be retracted by loading cartridges into the magazine. When it is desired to remove the magazine, the stock is removed and the plunger 28 retracted to an extent allowing dropping out or removal of the washer 38 whereupon, of course, it is a simple matter to retract the magazine from aperture 24 and remove it from the firearm completely.

To replace the magazine, the reverse procedure is used, i. e., the cartridge follower end of the tube 32 is placed in the aperture 24, the plunger is pushed back, the washer 38 is inserted, and the plunger is then allowed to extend forwardly into stud 26 through the washer. A small dent 40 may be utilized to prevent unwanted excess recoil of plunger 28 but this dent is not large enough to interfere with retraction of the plunger under pressure, as by the operator.

It will be seen that this invention provides a very simple magazine of the class described which is easily assembled and disassembled and which is completely housed within the fore end 16 even though the shotgun with which it is used is a repeating firearm.

Having thus described my invention and the advantages thereof, I do not wish to be limited to the details herein disclosed, otherwise than as set forth in the claims, but what I claim is:

1. Magazine fastening device for shotguns and the like comprising a barrel, a receiver, a magazine underlying the barrel and having a detachable connection with the receiver, a stud on the barrel spaced from the receiver, a magazine spring for pressing cartridges toward the receiver, a plunger pressed by the magazine spring in the opposite direction toward the stud, said plunger engaging the stud and holding the magazine thereto, the plunger being retractable against the spring therefrom to release the magazine.

2. Magazine fastening device for shotguns and the like comprising a barrel, a receiver, a magazine underlying the barrel and having a detachable connection with the receiver, a stud on the barrel spaced from the receiver, a magazine spring for pressing cartridges toward the receiver, a plunger pressed by the magazine spring in the opposite direction toward the stud, said plunger engaging the stud and holding the magazine thereto, the plunger being retractable against the

spring therefrom to release the magazine, and a washer between the stud and the magazine, the plunger holding the washer in position.

3. Magazine fastening device for shotguns and the like comprising a barrel, a receiver, a magazine underlying the barrel and having a detachable connection with the receiver, a stud on the barrel spaced from the receiver, a magazine spring for pressing cartridges toward the receiver, a plunger pressed by the magazine spring in the opposite direction toward the stud, said plunger engaging the stud and holding the magazine thereto, the plunger being retractable against the spring therefrom to release the magazine and a washer between the magazine and stud, the plunger holding the washer in the magazine.

4. A firearm of the class described comprising a barrel, a receiver, a stock, a magazine tube, a stud on the barrel, a stud on the receiver, the receiver stud having an opening therein into which the rear end of the magazine tube extends for a detachable connection therewith, a magazine spring, a plunger at the forward end of the magazine, said spring urging the plunger outwardly of the magazine toward and into engagement with the barrel stud, and a loose washer between the magazine and plunger, the latter extending through the washer into the barrel stud.

5. A firearm of the class described comprising a barrel, a receiver, a stock, a magazine tube, a stud on the barrel, a stud on the receiver, the receiver stud having an opening therein into which the rear end of the magazine tube extends for a detachable connection therewith, a magazine spring, a plunger at the forward end of the magazine, said spring urging the plunger outwardly of the magazine toward and into engagement with the barrel stud, and a loose washer between the magazine and plunger, the latter extending through the washer into the barrel stud, said stock enclosing the entire magazine, and a fastener securing the stock to the receiver stud.
